UNITED STATES PATENT OFFICE.

JOSEPH BENOSCH, OF AMSTERDAM, NEW YORK, ASSIGNOR TO KLAUDER-WELDON
DYEING MACHINE COMPANY, OF AMSTERDAM, NEW YORK, A CORPORATION OF
NEW YORK.

DYEING-MACHINE.

1,121,064.

Specification of Letters Patent.

Patented Dec. 15, 1914.

Application filed March 9, 1914. Serial No. 823,496.

To all whom it may concern:

Be it known that I, JOSEPH BENOSCH, a citizen of the United States, residing at Amsterdam, in the county of Montgomery and State of New York, have invented certain new and useful Improvements in Dyeing-Machines, of which the following is a full, clear, and exact description, such as will enable others skilled in the art to which it appertains to make and use the same.

This invention relates to dyeing apparatus and the like.

One of the objects thereof is to provide simple, durable and reliable means for securing in operative position supporting sticks or like devices for dyeing machines.

Another object is to provide means of the above type adapted for rapid and convenient manipulation.

Other objects will be in part obvious, and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein are shown one or more of various possible embodiments of the several features of this invention, Figure 1 is a diagrammatic elevation of a portion of a rotary carrier and associated parts; Fig. 2 is a side view of stick supporting and retaining mechanism; Fig. 3 is a sectional view taken along the lines $x-x$ of Fig. 2; Fig. 4 is a perspective detail view of a spring retracting device; and Fig. 5 is a side elevation of a slightly different form of supporting and retaining mechanism.

Similar reference characters refer to similar parts throughout the several views of the drawings.

Referring now to Fig. 1 of the drawings, there is shown a pair of rotary carriers or spiders 1 and 2 mounted upon the shaft 3 in the well-known manner. The illustrative embodiment of this invention here described shows its adaptation to a skein dyeing machine of a well-known type, comprising a

pair of rotary carriers between and upon which are supported dye sticks radially disposed in pairs about the carrier for supporting yarn and the like.

Certain features of this invention are obviously adaptable for use in other relations, and it is to be noted that the term "dyeing" as herein used is intended to have a broad significance as comprehending analogous operations, such as washing and the like.

The sticks 4 are supported upon carrier 2 by ratchet devices 5 driven by star wheels 6, this mechanism being here indicated diagrammatically, as its details form no part of the present invention. The remaining ends of sticks 4 rest within the cups or sockets 7 which are concentrically disposed about the shaft 3. Each of these sockets is rigidly held in position and is preferably provided with a lip or extension 8 for a purpose hereinafter described. Coacting with a plurality of these sockets, in this instance three, is a slide 9 which rests within the flange 10 of the carrier and is held against the web 11 of the carrier by rivet pins 12 passing through slots 13 and secured in pairs to caps or retaining devices 14, one for each of the cups 7. Each of the retaining caps 14 is provided with an extension or lip 15, which is flared with respect to the lip 8 upon the cup 7.

It is to be understood that the term "cup" is here used broadly to denote any analogous form of supporting device.

In the use of this apparatus, the squared ends of the stick 16 are first inserted within the squared sockets in lips 15 and then the rounded ends 17 are swung or forced laterally between the lips 15 and 8 of the opposite cup and retaining devices 7 and 14. The part 14 is then moved laterally away from its position over cups 7 to permit the round end of the stick to pass into the socket, this movement being resisted by a spring 18, which is secured as by screw or rivet 19 to the flange 10 at one end, and the opposite end to a lug 20 upon the slide 9. As the stick end 17 reaches a position within the socket 7 this spring snaps the slide with associated parts back into their normal position, and the next stick may be inserted

within the next cup 7 in a similar manner. The single spring 18 thus serves to retain in operative position a plurality of locking devices, working with full effectiveness in each device, and hence the number of required springs is reduced to a small fraction of that usually employed, and at the same time the machine is simplified and cheapened.

When it is desired to remove the stick, each cap or retaining device may readily be forced away from the corresponding cup by means of lug or lip 15, and the stick removed. In this manner the machine may be quickly loaded and unloaded, and yet the sticks are firmly held in position, for no outward movement tends to slide the caps into a position to permit accidental release, and even the rotary movement of the sticks has no such tendency upon these sliding caps.

In Fig. 5 of the drawings is shown a slightly different embodiment of certain features of this invention, in which the cups 21 are much shorter and the caps 22 are correspondingly lengthened, and provided with the lips or extensions 23 as well as lips 24. The mounting of these caps is substantially identical with those above described, and the loading of the stick within the sockets is closely similar. The unloading, however, is accomplished by a lateral swing of the stick in the same direction in which it entered the cup, that is, the direction indicated by the arrow 25, the stick passing out between the lip 23 and the adjacent edge of the cup. In this manner the speed and convenience of removing the sticks is somewhat enhanced.

It will thus be seen that there is provided apparatus in which the several objects of this invention are achieved and which is well adapted to meet the conditions of the hardest practical use without deterioration or breakage of the parts.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In dyeing apparatus or the like, in

combination, a plurality of stick supporting devices, a plurality of devices respectively coacting with said first devices to retain said sticks therein, and a single spring urging said retaining devices toward operative position.

2. In dyeing apparatus or the like, in combination, a plurality of cups, each adapted to receive and support the end of a stick, a plurality of devices respectively coacting with said cups to retain the sticks therein, and a single spring urging said closing devices toward operative position.

3. In dyeing apparatus or the like, in combination, a plurality of cups each adapted to receive and support a stick, a slide, a plurality of closing members upon said slide respectively adapted to coact with and retain the sticks in said cups, and a spring urging said slide to bring said closing members into operative relation to said cups.

4. In dyeing apparatus or the like, in combination, a rotary carrier for sticks, a supporting cup upon said carrier, and a spring retracted slide adapted to permit the end of a stick to be forced laterally within said cup.

5. In dyeing apparatus or the like, in combination, a rotary carrier, a supporting cup on said carrier and opening away from the axis of said carrier, a member slidably mounted upon said carrier and adapted in one position to retain a stick within said cup, said member being provided with a lateral extension adapted to be engaged by the end of the stick as it is forced within said cup.

6. In dyeing apparatus or the like, in combination, a carrier, a plurality of supporting cups mounted upon said carrier each adapted to receive and support the end of a stick, a slide upon said carrier, a plurality of devices upon said slide respectively coacting with said cups and adapted to permit a stick to be forced laterally within said cups, and a single spring urging said devices into operative relation to said cups.

7. In dyeing apparatus or the like, in combination, a carrier, a plurality of stick supporting devices upon said carrier, a plurality of devices respectively coacting with said first devices to retain said sticks therein and provided with extensions adapted to be engaged by the ends of the sticks as they are forced laterally within said cups, and a single spring urging said retaining devices toward opposite position.

8. In dyeing apparatus or the like, in combination, a rotary carrier, a plurality of cups concentrically arranged about the axis of said carrier and mounted thereon, a slide upon the carrier, a plurality of retaining devices respectively coacting with said cups,

each of said cups and the corresponding retaining device being respectively provided with extended portions adapted to receive therebetween the end of a stick, and a single
5 spring urging said slide toward a position in which said retaining devices are in operative relation to said cups.

In testimony whereof I affix my signature, in the presence of two witnesses.

JOSEPH BENOSCH.
